CLAIM

The ornamental design for a cone-shaped container, as shown and described.

DESCRIPTION

FIG. 1 is a top perspective view of a cone-shaped container showing my new design;
FIG. 2 is a side elevation view thereof, the opposing side elevation view being identical;
FIG. 3 is a top plan view thereof;
FIG. 4 is a bottom plan view thereof;
FIG. 5 is a bottom perspective view thereof; and,
FIG. 6 is a cross-section view taken in the direction of line 6-6 in the FIG. 2 drawing view.
